UNITED STATES PATENT OFFICE

114,456

DESIGN FOR A ROTATABLE ADVERTISING SIGN

Alexander McCabe and Adele McCabe, San
Francisco, Calif., assignors to Acme Breweries,
a corporation of California

Application January 24, 1939, Serial No. 82,554

Term of patent 7 years

To all whom it may concern:

Be it known that we, Alexander McCabe and Adele McCabe, both citizens of the United States and residents of the city and county of San Francisco, and State of California, have invented a new, original, and ornamental Design for a Rotatable Advertising Sign, of which the following is a specification, reference being had to the accompanying drawing, forming part thereof, in which:

Figure 1 is a side elevation of a rotatable advertising sign embodying our new design; and Figure 2 a top plan view thereof.

We claim:

The ornamental design for a rotatable advertising sign, substantially as shown.

ALEXANDER McCABE.
